UNITED STATES PATENT OFFICE

135,583

DESIGN FOR A STATUETTE OR SIMILAR ARTICLE

Vernon H. Tabor, Cincinnati, Ohio

Application August 19, 1942, Serial No. 107,966

Term of patent 7 years

To all whom it may concern:

Be it known that I, Vernon H. Tabor, a citizen of the United States of America and a resident of Cincinnati, in the county of Hamilton and State of Ohio, have invented a new, original, and ornamental Design for a Statuette or Similar Article, of which the following is a specification, reference being made to the accompanying drawing, forming a part thereof.

Fig. 1 is a front elevational view of the statuette showing my new design.

Fig. 2 is a rear elevational view of the statuette.

Fig. 3 is a top plan view of the statuette as illustrated in Fig. 1.

I claim:

The ornamental design for a statuette or similar article, as shown.

VERNON H. TABOR.
